SUPERHEATER

Application filed November 20, 1930. Serial No. 498,030.

Steam engineering indicates broadly the field to which this invention pertains. More particularly it is concerned with improvements in steam superheaters which are subjected to radiant heat.

In this art it was long held by engineers, competent and experienced in the art, that radiant heat superheaters were not practical and that the problems to be solved to enable them to be used effectively were insurmountable. The excessive heat to which they are subjected causes conditions of operative unbalance on account of the fact that the steam flow through the superheaters would be reduced or stopped at times when the exposed portions of the tubes were still receiving excessive amounts of heat from the furnace. The excessive heat to which the tubes are subjected at times causes severe distortion of the tubes by reason of the great expansion involved. Different attempts to use such superheaters have shown that the unequal expansion on different sides of the tubes causes distortion and displacement of the tubes with consequent disruption of the superheater wall.

It has been proposed to solve such problems by providing structures for fixedly maintaining the individual superheater tubes in their original positions. It has also been proposed to provide a number of ties rigidly connected to the superheater tubes and distributed throughout the height of the wall for thus holding them. Such proposals have not proved effective because of their tendency to impose local strains upon the tubes and cause local failures. Such proposed structures have also been excessively expensive.

It is an object of the present invention to present an effective solution to the problems above indicated and to provide apparatus which will continuously maintain the integrity of the superheater wall.

Another object of the invention is to permit the superheater tubes to have such movements in unison that the superheater wall is maintained as a complete furnace closure element at all conditions of temperature and heating.

A further object is to provide a superheater in which the expansion and contraction movements of the tubes are caused to produce predetermined changes in the wall of tubes subjected to radiant heat.

Other objects of the invention will appear as the accompanying description proceeds.

This invention is described with reference to the accompanying drawing, in which:

Fig. 1 is mainly a vertical section showing the illustrative structure.

Fig. 2 is an exterior elevation showing the manner in which the superheater headers are related.

In the drawing the superheater tubes 10 form, with the refractory wall 12, a flexible curved side of a boiler furnace 14. At their ends, the tubes communicate with headers 16 and 18.

Change in curvature of the superheater wall takes place when the temperature of the wall is changed. In the present instance the superheater wall is set up so as to extend along a wide curve, the midportion of the wall being slightly nearer the center of the furnace than the ends of the wall. When divergent movement of the ends of the wall is restricted or retarded, the curvature of the wall increases as the wall temperature increases.

Restriction or retardation of divergent movement of the ends of the superheater wall is effected by the connectors 20 which tie together the headers 16 and 18 outside of the wall. Each connector comprises a turnbuckle 22, turnbuckle rods 24 and 26, and header anchors 28, 30.

In Fig. 1 the connectors 20 pendently support the lower header 18 in such a manner that the relative positions of the headers may be controlled to insure the functioning of the superheater wall in the manner above indicated. By bringing the headers slightly toward each other the bowing action of the superheater wall under temperature changes can be governed. By the same device other movements of the superheater parts caused by the forces of expansion and contraction can be accommodated.

The entire superheater structure is hang-

ingly supported from a fixture 32 preferably extending along and above the header 16. In the drawing the means for accomplishing such support include anchors 34 having tension members 35 pivoted thereto. The members 35 are supported by cross plates 36 resting upon the fixture 32. With this construction movements of the upper portions of the superheater to and from the furnace center are accommodated.

10 The superheater structure is maintained in its operative position by guides herein shown as parallel uprights 38 and 40 straddling the lower header 18. These guides also maintain operative relationships of the superheater parts when adjustments are effected.

15 The uprights 38 and 40 are illustrated as affixed to a bracket 42 preferably secured to the fixed wall 44 forming a side of the boiler furnace construction.

20 Adjacent the upper header 16 the superheater is arranged relative to the upper furnace wall 46 so as to maintain a substantially gas-tight furnace side, but to provide for the lateral shifting of the superheater wall under the influence of temperature changes. The arrangement illustrated includes a head 48 formed of heat resisting material. This head is an extension of the wall 12 and is 25 formed with a shoulder 50 which under extreme conditions can contact with a complementary shoulder 52 formed on the furnace wall 46. Adequate clearance between the upper bends 54 of the superheater tubes and 30 a correspondingly curved portion 56 of the upper furnace wall accommodates the curvature change of the superheater tubes attendant upon a change in temperature.

35 Near the lower header 18 the flexibility and change in temperature of the superheater wall is permitted by a construction including a joint seal 58 preferably closely fitting the superheater tubes. This seal overlaps a shoulder on the lower furnace wall 44 in such a manner that it slides along that shoulder when the lower header shifts vertically with respect to the upper header. The lower end 62 of the wall 12 extends along the lower parts 64 of the tubes 10 and abuts 50 against the seal 58 in a gas-tight relationship.

40 Adequate clearance between the lower bends of the tubes 10 and the furnace wall 44 is provided. The latter wall is formed 55 with an upstanding portion 66 preferably formed with a surface curved similarly to the curve of the lower bends of the tubes 10 and spaced therefrom to allow inward bowing of the tubes without contact between the tubes and the wall.

45 By use of a plurality of connectors 20 arranged along the length of the headers 16 and 18, the latter are maintained in parallelism. When the superheater tubes are 50 equally heated this arrangement of elements

further assures such uniform bowing of the tubes that the integrity of the superheater wall is maintained. The interposition of heat resisting material relative to the superheater tubes prevents lateral displacements 70 of the tubes with consequent interference with uniform steam flow.

5 The illustrative superheater is indicated in connection with a water tube boiler construction having a header 68, slag screen 75 tubes 70 and water tubes 72; 74 indicates a part of a boiler casing construction outside of the header 68.

10 Although this invention has been described with reference to the specific structure shown in the drawings it is to be understood that it is not limited thereto but is of a scope commensurate with the scope of the subjoined claims.

15 What I claim as new, and desire to secure 85 by Letters Patent, is:

1. Apparatus of the character described comprising, in combination, a furnace, a superheater entrance header, an exit header, connectors extending from one header to the 90 other and secured thereto to maintain the operative relationship of the headers and to suspend the lower header from the upper, steam flow tubes formed as a furnace wall and connected into header circulation and 95 having bowed parts forming a curved wall presented to the radiant heat of the burning fuel in the furnace, and means connecting said parts to the headers.

2. A steam superheater comprising, in combination, an entrance header, means for pendentially supporting said header, an exit header, connectors tying the headers together and pendentially supporting one from the other, and superheater tubes forming with the 100 headers a steam circulating unit, said tubes having their midportions formed on the arc of a circle of a radius sufficiently large to enable the portions to constitute a part of an upright furnace wall.

105 3. A steam superheater having upper and lower headers, means for suspending the superheater from the upper header, a series of adjustable tie members between the upper and lower headers, means for connecting the tie members to the headers at uniformly spaced positions throughout the length of the headers, and guides for maintaining the lower header within the same vertical confines as it moves in response to expansion and contraction.

110 4. In a boiler structure, a combustion chamber, a bank of steam superheater tubes exposed to the radiant heat of burning fuel in the combustion chamber, an upper header for the superheater tubes, a lower header for the superheater tubes, means for suspending the superheater structure, connectors for tying together the upper and lower headers, and parallel guides for maintaining the lower 115 120 125 130

header in its normal position as varying temperatures in the superheater structure cause expansion and contraction of the structure.

5. A steam superheater, inlet and outlet headers, a row of bowed tubes connecting said headers, means for suspending the superheater, a series of tie members extending directly from one header to the other, means for connecting the tie members to the superheater headers, and guides for maintaining the lower of said headers within the same vertical confines as it moves in response to expansion and contraction.

6. In a radiant steam superheater, a furnace wall, inlet and outlet superheater headers located externally of the furnace wall, a row of adjustable tension members fixed to the headers and extending directly from one to the other, and a row of bowed superheater tubes communicating with the headers and exposed to radiant heat from the furnace.

7. A flexible furnace wall section comprising, in combination, a row of fluid conducting tubes bowed inwardly toward the center of the furnace throughout their lengths exposed to radiant heat from the furnace, a heat resisting layer forming a backing for the row of tubes, an inlet header connected to the inlet ends of the tubes, an outlet header connected with the outlet ends of the tubes, and means directly extending from one header to the other to tie them together.

8. A radiant superheater comprising, in combination, a fixed furnace wall section, a second fixed furnace wall section spaced from the first, a row of bowed fluid conducting tubes extending from one of said sections to the other, a suspended superheater inlet header located externally of the sections, a suspended superheater outlet header similarly located, means directly tying the headers together, upper and lower tube extensions extending across the opposed faces of said sections to connect the headers with the adjacent ends of the bowed tubes, a refractory layer supported by the tubes, and extensions to form with the sections a gas tight furnace wall, one set of said extensions being spaced from the adjacent face of the adjacent wall section to take care of tube expansion, and a seal member movable with the extensions to close the space adjacent the last mentioned extensions.

9. A fluid heat exchange device having upper and lower headers, a combustion chamber, a bank of fluid conducting tubes exposed to the radiant heat of burning fuel in the combustion chamber and connected to said headers, means for suspending the device from the upper header, a series of adjustable tie members between the upper and lower headers, means for connecting the tie members to the headers at uniformly spaced positions throughout the length of the headers, and guides for maintaining the lower header

within the same vertical confines as it moves in response to expansion and contraction.

10. In a fluid heat exchange device, a combustion chamber, a bank of fluid conducting tubes exposed to the radiant heat of burning fuel in the combustion chamber, an upper headed for the tubes, a lower header for the tubes, means for suspending the structure, connectors for tying together the upper and lower headers, and parallel guides for maintaining the lower header in its normal position as varying temperatures in the structure cause expansion and contraction of the device.
